UNITED STATES PATENT OFFICE.

GEORGE T. GLOVER, OF CHICAGO, ILLINOIS.

GUN.

SPECIFICATION forming part of Letters Patent No. 864,848, dated January 1, 1901.

Application filed June 25, 1900. Serial No. 21,482. (No model.)

To all whom it may concern:

Be it known that I, GEORGE T. GLOVER, a citizen of the United States, residing at Chicago, in the county of Cook and State of Illinois, have invented a certain new and useful Improvement in Guns, of which the following is a specification.

My invention relates to that class of guns or cannon which are commonly known as "built-up" guns and which are composed of a plurality of concentric tubes. These tubes have generally been shrunk together—that is to say, one upon the other—in such manner as to render them practically one. This process of shrinking is, however, slow and expensive and is open to the further objection that a uniform shrinkage of the tubes is impossible. Consequently there is always a liability, for instance, of the outer jacket being shrunk to an extent to compress the others, and in such case it is obvious that the jacket thus unduly shrunk will be compelled to sustain more than its proper proportion of the bursting strain.

The principal object of my invention is therefore to avoid this costly and unsatisfactory process of shrinking and to provide an improved method which will be at once simple, economical, and highly effective.

Certain special objects are to permit a relative longitudinal shift or adjustment on the part of the concentric tubes or jackets and to thereby provide a gun in which the force of the explosions may be utilized to effect a uniform tightening of the jackets and a consequent equalization of the strain, to provide a construction involving a plurality of tapered tubes assembled so as to be capable of relative shift and separated by interposed layers of non-conducting material, to lock the tubes or jackets against relative twist or rotation, to facilitate the opening of the breech of the gun, and to provide certain details tending to increase the general efficiency.

A built-up gun constructed in accordance with my invention consists of an inner tube tapered externally toward the muzzle and one or more tapered jackets arranged thereon. If but one jacket is provided, it is tapered internally to fit the tube; but if several jackets are employed all except the outermost will be tapered internally and externally, so as to

fit one upon the other. Each successive jacket is desirably made somewhat shorter than the one over which it is drawn or placed, and the said tubes and jackets are preferably assembled so as to be capable of a relative and longitudinal shift or adjustment. The breech-block is secured within the rear end of the outer jacket, which latter extends somewhat beyond or to the rear of the tube and also of the other jackets, if more than one are employed, whereby the recoil and forward pull of the projectile will tend to give the jacket or jackets a slight end movement toward the rear and the tube a similar movement forward. In this way the force of the explosion is utilized to tighten the jackets upon the tube and also upon each other. The more the gun is fired the more firmly the jackets embrace the tube and each other, and as the said tube and jacket or jackets are all tapered alike such tightening will necessarily be of a uniform and like nature—that is to say, the jackets will all be tightened alike and in such manner as to permit each to sustain its proper share of the strain. If so desired, the tapered tubes thus assembled so as to be capable of relative shift can be separated by interposed layers of asbestos or similar material, and by so doing the heat and vibration incident to firing will be confined or limited to the center of the gun.

While for the broader purposes of my invention any style or construction of breech-block could be employed, I prefer, as a matter of further and special improvement, to use a breech-block consisting of a slightly tapered or wedge-shaped block arranged to extend transversely through the rearwardly-extended portion of the outer jacket, and as a matter of still further improvement the said breech-block is adapted to lock the tube and jackets against relative twist or rotation. The breech-block could be operated by any well-known mechanical device; but with a view to facilitating such operation I have arranged to shift the block by means of a small quantity of powder exploded within a cavity or chamber located at the inner end of the said breech-block.

With reference to the accompanying drawings, Figure 1 represents in side elevation a built-up gun constructed in accordance with

my invention. Fig. 2 is a vertical central longitudinal section through the same, showing a cartridge in position to be fired. Fig. 3 is a horizontal central longitudinal section through the gun, the muzzle or forward portion of the same being broken away. Fig. 4 is a transverse section on line $\alpha\alpha$ in Fig. 1. Fig. 5 is a transverse section on line $\alpha'\alpha'$ in Fig. 1.

10 The foregoing figures illustrate a built-up gun comprising an inner tube A, a couple of superimposed jackets B and C, and a breech-block D. The tube A, it will be observed, is slightly tapered externally from the breech 15 to the muzzle and provided with a bore a, which may be rifled or not, according to requirements. Jacket B is tapered its full length internally to fit upon the tube A and is also tapered externally to receive the second and outer jacket C, it being observed that the meeting surfaces of the said tube and jackets are all parallel, the taper being the same in each case. The jacket B is preferably somewhat shorter than the tube A 25 and the jacket C shorter than the jacket B, the exposed portion b of jacket B being thinned down and the exterior of jacket C having a more pronounced taper than its interior, the gun thus finished having, as shown, 30 a neat appearance and a pronounced taper from breech to muzzle. The interposed layers of asbestos E will tend to limit or confine the heat and vibration incident to firing to the tube A, and thereby prolong or extend 35 the life of the jackets, the tube A when worn or weakened by use being removed and replaced by a new one. While I have described the gun as composed of a tube and jackets with interposed layers of asbestos, I do not 40 limit myself to the use of such material, as there are numerous substances which are poor conductors of heat and vibration.

With reference now to the breech-block, it will be observed that the outer jacket D is 45 extended beyond and to the rear of the tube A and jacket B and that the said breech-block extends transversely through such rearwardly-extended portion. The forward surface d of the block is preferably straight or 50 at right angles with the bore of the gun and the rear surface d' slightly beveled or inclined, thereby giving the block a wedge-like shape or form. By this arrangement it will be seen that the entire rearward thrust or recoil will be sustained by a breech-block which 55 is secured to the outer jacket only and that the effect of such arrangement will be a slight relative shift on the part of the tube and jackets similar to the extending of a telescope. The force of the explosion exerted 60 upon the breech-block will tend to draw one or more of the jackets rearward, while the friction or forward pull of the projectile on the bore of the tube will tend to draw the latter and perhaps one or more of the jackets 65 forward. For instance, should jacket B before firing be tighter upon the tube A than

jacket C upon the said jacket B the recoil will tend to draw jacket C rearward, while the forward pull of the projectile will tend to 70 shift tube A and jacket B forward until the jacket C embraces jacket B with the same degree of force that jacket B embraces the tube A, beyond which point there will be an equal amount of relative shift between C 75 and B and between B and A. In this way, it will be seen, the shock or force of the explosion instead of tending to loosen or disrupt the different parts of the gun will tend to tighten the jackets and equalize the strain 80 thereon.

As a matter of further improvement the breech-block is adapted to serve as a key for the purpose of locking the tube and jackets against relative twist or rotation. By referring to Figs. 2, 3, and 4 it will be seen that the breech-block extends transversely through the jacket C by way of a couple of openings c c' and also that the said block engages notches formed in the rear ends of the tube 90 A and jacket B. The notching of the rear ends of the said tube A and jacket B provides, in effect, a pair of cheeks a' a' on tube A and a similar pair b' b' on jacket B. (See Figs. 3 and 4.) The said cheeks extend a 95 short distance rearward on each side of the breech-block, (see Fig. 3,) and by such arrangement the latter is enabled to lock the tube and jackets against relative twist or rotation. 100

The firing pin or needle F is also a feature of improvement, being made in two parts f and f' and provided with a head f² to prevent the expanding gases from escaping rearward through the needle-hole. 105

While, as previously stated, various mechanical contrivances or even the hand in the case of a small gun could be employed for shifting or opening the breech-block, I prefer, with a view to simplifying such operation, to raise or shift the block by means of a small charge of powder or other explosive exploded at the inner end of the said block. To this end I have arranged upon the jacket C a short sleeve G, provided with an opening 115 g coincident with the opening c and having a shallow cavity g' formed on its interior surface. The said cavity, with the lower surface d² of the breech-block, forms a chamber wherein a small quantity of explosive 120 may be exploded, with the result that the breech-block will be forced outward to an extent sufficient to permit loading. An arch H limits the outward movement of the breech-block, and a spring-bolt I, adapted to engage 125 the recess d³, serves to hold the block in an elevated position, it being necessary, of course, to remove the rear portion f' of the pin F before so shifting the block.

Obviously any known hammer or firing 130 mechanism may be employed to operate the pin F and to explode the charge in the cavity g', it being also obvious that a recess or cavity in the lower end of the breech-block would

be the equivalent of the present arrangement and that the sleeve G could be dispensed with by making the outer jacket C somewhat thicker.

5 Thus it will be seen that I provide a simple and practical construction of built-up gun, that the relative formation of the tube and jackets is such that the forward pull of the projectile upon the tube and the rearward pressure of the expanding gases upon the breech-block and outer jacket will operate to maintain the tube and jackets in place—that is to say, will operate to keep each jacket properly seated—that the construction enables 10 the breech-block to serve as a key for preventing relative twist or rotation on the part of the tube and jackets, and also that with my arrangement the construction can be such as to permit an advantageous use of interposed layers of asbestos.

15 What I claim as my invention is—

1. A built-up gun comprising an inner tube, a plurality of concentric jackets arranged upon the said tube, and a breech-block secured to the outermost of said jackets, the relative formation of the tube and jackets being such that the forward pull of the projectile upon the tube and the rearward pressure of the expanding gases upon the breech-block and outer jacket will operate to maintain 20 the tube and jackets in place.

2. A built-up gun comprising an inner tube tapered toward the muzzle, and one or more tapered jackets; a wedge-shaped breech-block extending transversely through the rear end of the gun, and arranged to engage and lock the said tube and jacket or jackets against relative twist or rotation; a firing-pin extended through the breech-block, and 35 means whereby the said block may be shifted so as to open the breech of the gun.

3. A built-up gun comprising a plurality of tapered tubes arranged one upon the other with interposed layers of asbestos or like material, and a breech-block extending transversely through the rear end of the outer tube, whereby the recoil and the forward pull of the projectile will tend to tighten the said tubes upon each other; the said breech-block 45 also being arranged to engage and lock the tubes against relative twist or rotation.

4. A built-up gun comprising a plurality of concentric tubes keyed or locked against relative twist by a transversely-arranged breech-block.

5. A built-up gun comprising a plurality of tapered tubes keyed or locked against relative twist by a transversely-arranged breech-block.

6. A built-up gun comprising an inner tube tapered externally toward the muzzle, a plurality of internally and externally tapered jackets arranged upon the said tube, and a breech-block suitably secured to one or more 65 of the outer jackets; the taper of the said tube

and jackets being substantially the same whereby the relative shift caused by the force of the explosion will be of a character to permit each jacket to sustain its proper share of the bursting strain.

7. A built-up gun comprising a tapered tube and a plurality of tapered jackets assembled so as to be capable of relative longitudinal shift, and having a breech-block secured to its outer jacket in such manner that the force 70 of the explosions will cause a relative longitudinal shift on the part of the said tube and jackets, resulting in a tightening of the latter upon the former and also upon each other.

8. A built-up gun comprising a plurality of 75 tapered tubes with interposed layers of non-conducting material; the said tubes being assembled so as to be capable of a relative longitudinal shift, and the outer tube being provided with a breech-block, by which arrangement the force of the explosions will cause a 80 relative longitudinal shift on the part of the said tubes.

9. A gun comprising a tapered tube and a plurality of tapered jackets with interposed 85 layers of non-conducting material; the said tube and jackets being assembled in such manner as to admit of a relative longitudinal shift, and the taper of the jackets being substantially the same, whereby the relative shift 90 or adjustment caused by the force of the explosions will be of a nature to enable each jacket to sustain its proper share of the strain.

10. A built-up gun comprising an inner tube tapered toward the muzzle and having 100 its rear end notched; one or more tapered jackets arranged upon said tube and having their rear ends similarly notched; an outer jacket having its rear end provided with a transverse opening in line with said notches, 105 and a wedge-shaped breech-block extending through said opening and engaging said notches; the said breech-block being adapted to lock the said tube and jackets against relative twist or rotation, and also to form a backing for the explosion, whereby the recoil and the forward pull of the projectile will tend to give the tube and jackets a relative longitudinal shift.

11. A built-up gun comprising a tapered inner tube, a tapered outer jacket, one or more intermediate jackets having a similar or corresponding taper, and a breech-block secured to the said outer jacket; the tube and jackets being assembled so as to permit a relative 115 longitudinal shift, and the firing of the gun operating to equalize the strain by reason of the recoil being applied to the outer jacket in a rearward direction and the pull of the projectile to the inner tube in an opposite direction.
